UNITED STATES PATENT OFFICE

IVER A. HANSEN, OF AURORA, ILLINOIS, ASSIGNOR TO INDEPENDENT PNEUMATIC TOOL COMPANY, OF CHICAGO, ILLINOIS, A CORPORATION OF DELAWARE

PNEUMATIC TOOL

Application filed December 18, 1922. Serial No. 607,498.

This invention relates to piston actuated pneumatic or other fluid operated tools of the portable type, and has particular reference to the counter-weighting of the crank shaft at both ends to properly balance the shaft and secure a perfectly running tool.

One object of my invention is to have the counter-weight at one end of the shaft removable so that the shaft, before the said counter-weight is applied, may be inserted through the bearing sleeves and eccentric straps of the rods connecting the pistons and valves with said shaft in assembling the tool and thus employ solid or one-piece sleeves and straps for the pistons and valves, respectively.

Another object of the invention is to provide at the removable counter-weight a tension plate for holding the crank shaft against endwise movement.

A further object of my invention is to provide improvements in the one-piece bearing sleeves for the connecting rods and to also provide a novel means of releasably connecting the valves with their eccentric straps.

The invention consists further in the matters hereinafter described and more particularly set forth in the appended claims.

In the accompanying drawings—

Fig. 1 is a longitudinal sectional view through the central portion of a pneumatic drill embodying the features of my invention;

Fig. 2 is a transverse vertical sectional view taken on line 2—2 of Fig. 1;

Fig. 3 is a transverse vertical sectional view taken on line 3—3 of Fig. 1;

Fig. 4 is a like view showing the removable counter-weight removably connected with the crank shaft in a manner different from that indicated in Fig. 3;

Figs. 5 and 6 are transverse sectional views taken on lines 5—5 and 6—6 respectively, of Fig. 1;

Fig. 7 is a longitudinal sectional view taken on line 7—7 of Fig. 5;

Fig. 8 is a view of the split ring for holding the eccentric straps on the crank shaft;

Fig. 9 is a view of one of the split rings for the bearing sleeves of the connecting rods; 50 and

Fig. 10 is a view showing a bearing sleeve of a connecting rod with split retaining ring removed.

The drill shown in Fig. 1 has an outside casing divided into connected sections 1 and 2. The main or rearmost section 1 contains the crank shaft 3, and the forward section 2 the drill spindle 4. These two parts, in the particular structure shown in Fig. 1, are in alignment and are geared together so that power may be transmitted from the crank shaft 3 to the spindle 4. The latter carries the usual tool holding chuck (not shown) at its forward end, and the section 1 carries on the outside cylinder blocks 5, 5 arranged at an angle and on opposite sides of the crank shaft 3.

Each cylinder block 5 is provided with two power cylinders 6, 6 and an interposed valve cylinder 7. In each power cylinder is a piston 8 and in each valve cylinder 7 is a reciprocating valve member 9. Each piston 8 and valve member 9 are connected with the crank shaft 3 in a manner to be presently described. The valve members 9, 9 control the supply and exhaust of motive fluid to and from the power cylinders 6, 6, there being a suitable arrangement of ports and passages for this purpose. As these do not form part of my present invention, there is no need to describe them. The power and valve cylinders 6, 7 are lined with removable wear resisting bushings 10, 11, held in place by head plates 12, 12 secured to the cylinder blocks, as shown. This construction forms the subject-matter of the copending application of Reinhold A. Norling, filed December 18, 1922, Serial No. 607,619, now Patent No. 1,529,911.

The crank shaft 3 has its forward end, that is, its end adjacent the drill spindle 4, supported by an antifriction bearing 13 in the forward end of the casing 1. The opposite end of the shaft 3 is supported by an antifriction bearing 14 in the block 15 of the tool handle 16. The latter is secured by bolts 17 to the rear end of the casing 1 and contains the usual valve controlled supply passage for the motive fluid for the tool.

One object of my invention is to counter-weight both ends of the crank shaft 3. This 100

gives a perfectly balanced shaft and secures a properly running tool. The counter-weight 18 at the forward end of the shaft 3 is fixed to the shaft. It is preferable to make this counter-weight rigid or solid with said shaft.

5 At the opposite or rear end of the shaft 3, I provide another counter-weight 19. This is removably mounted on the shaft. One form of obtaining a removable connection is shown in Figs. 1 to 3, while another form is shown in Fig. 4.

In the first form, the shaft 3 at the counter-weight 19 is provided with a number of flat faces 20 arranged part way around the shaft to make that portion of the same partly hexagonal in cross-section, as illustrated in Fig. 3. The remaining portion of the shaft is not milled but left round or circular, as at 21, to prevent the counter-weight 19 from being put on the wrong way. The bore of the counter-weight will have a shape complementary to that of the shaft part on which it fits. The portion of the shaft 3 immediately forward of the faces 20 and 21 is slightly enlarged to provide an annular stop shoulder 22. The other side of the shaft is reduced so that the counter-weight 19 may be slipped over the same when inserting it in place or removing it from the shaft upon dismantling the tool.

30 To hold the counter-weight 19 against the shoulder 22, the inner ring 23 of the bearing 14 fits against the same, as shown in Fig. 1. A washer 24 is held against the opposite side of this ring 19 by a clamp nut 25 on the threaded end of the shaft 3, as shown in Fig. 1. The outer ring 26 of said bearing 14 seats in an annular recess 27 in the block 15 of the handle 16, and said ring is held in said recess by a spring steel disc 28.

40 The disc 28 is normally flat; that is, when not in place in the tool casing, it has all portions in the same plane. The disc 28 is clamped in place between the overlapping parts of the handle block 15 and the casing 1, as shown in Fig. 1. The inner or central portion of the disc 28 overlaps the outer ring 26 to hold it in place. The casing 1 and handle part 15 being clamped together by the bolts 17 and the inner portion of the disc 28 resting against the bearing ring 26, causes the disc to be flexed into the shape shown in Fig. 1 when the parts are clamped together, and that flexing maintains the disc 28 against the bearing ring 26 and effectively holds it in place. By the structure described, the crank shaft 3 is held against endwise movement in both directions, in one direction by the handle block 15, and in the opposite direction by the disc 28.

60 The pistons 8, 8 in the power cylinders 6, 6 are connected with the crank shaft 3 by connecting rods 29, 29. Each connecting rod 29 is made in two main parts, one part being a continuous, one piece bearing sleeve 30 sur-

therefor, and the other part being a pitman or rod 31 having a ball and socket connection at one end with the associated piston 8 and a releasable connection at the other end with its bearing sleeve 30. This connection, as shown in Fig. 6 of the drawings, consists of a radial lug 32 on the bearing sleeve 30 to receive the inner end of the rod 31. The rod is screwed into the lug and the latter is split so that a clamp screw 33 may be used for holding the rod in place and against turning, as in Patent No. 1,391,847, granted September 27, 1921, to Reinhold A. Norling.

70 Anti-friction bearing balls 34 are interposed between each bearing sleeve 30 and the associated crank pin portion of the shaft 3. For these balls the shaft 3 and bearing sleeve 30 are grooved to provide race-ways 35, 35. For each sleeve 30, I provide a split retaining ring 36. This fits in the sleeve 30 on one side of the balls 34 and holds them in place. The opposite side of the race-way 35 in the sleeve 30 is formed to resist movement of the balls in that direction, as shown in Fig. 1.

75 In addition to the groove 35, the sleeve 30 has an internal annular groove 37 to receive the retaining ring 36. This groove opens outward through the sleeve 30 at one side through a gap or passage 38 (Fig. 10), and this accommodates the severed lugs 39 (Fig. 9) at the split end of the retaining ring 36, as shown in Fig. 6. The opposed sides of the gap 38 are grooved, as at 40, 40, to receive these lugs 39. The latter project radially outward beyond the sleeve 30 to be reached for contracting the ring 36 and removing it from the associated sleeve. This allows the sleeve 30 to be slipped over the inner end of the crank shaft 3 when the removable counter-weight 19 is off. The balls 34 are inserted into the race-way 35 through the gap 38 and held in place after the retaining ring 36 is inserted in place.

80 As shown in Fig. 1, the eccentric 41 of the crank shaft 3 is located between the two sets of connecting rods 29. About the eccentric 41 are two straps 42, 42, there being one for each of the valve members 9. Each strap 42 is made in one continuous and unbroken piece, like a solid ring, to surround the shaft 3 and fit on the eccentric portion 41 thereof. At one side of the eccentric 41, the shaft 3 is provided with an annular shoulder 43 to hold the strap 42 from displacement in that direction. At the other side of said strap there is a split retaining ring 44. This fits in a groove 45 in the crank shaft 3, and when in place holds the straps 42 on the eccentric 41.

85 Each valve member 9 has an inwardly projecting stem 46 (Fig. 7) and this carries a cross-pin 47. Each strap 42 has an outwardly projecting radial lug 48 overlapping the stem 46 of the associated valve 9 and provided with a hole to receive the pin 47, as shown in Figs. 130

5 and 7. This provides a releasable connection between the valves and straps 42.

The inner end of the casing 1 is open when the handle 16 is removed and allows the counter-weight 19 to be inserted therein when assembling the tool. The bearing sleeves 30 and straps 42 for the pistons 8 and valves 9 on opposite sides of the shaft 3 are arranged in pairs, as shown in Fig. 1. The parts of each pair have sideways engagement as shown. The cylinders 6 on one side of the crank shaft 3 have the longitudinal centers of their bores in line with the centers of the associated sleeves or rings 30. The cylinders 6 on the other side are offset to be in the same relation to their sleeves 30. The lugs 32 of said sleeves 30 are central with respect to their sleeves 30.

Providing the crank shaft 3 with two counter-weights 18 and 19, arranged on opposite sides of the power pistons and adjacent the connecting rods of the same, balances the shaft and insures a perfectly running tool, because the counter-weight 18 balances the connecting rods 29 next to it, and the counter-weight 19 does the same for the connecting rods 29 next to the same. This balances the crank shaft against the power strokes of the pistons in the power cylinders and secures a properly running balance for the tool. The counter-weight 19 at the inner end of the shaft 3 having removable connection therewith permits the use of one-piece sleeves 30 and straps 42 for the pistons and valves, respectively. With one-piece sleeves and straps, split parts and clamp bolts therefor are avoided. This makes the structure a jar proof one and one that is strong and compact by avoiding the use of joined parts and projecting bolts and lugs as heretofore.

In Fig. 4, I have shown a counter-weight 19^a releasably connected with the shaft 3 in a manner different from that in Figs. 1 to 3. As shown in Fig. 4, the shaft 3 is circular in cross-section at the counter-weight 19^a and fits in the like shaped bore thereof. A key 19^b is used as the connection between the shaft and counter-weight 19^a.

While I have shown and described herein in detail a structure of my invention, it is of course to be understood that the details of construction and arrangement of parts may be variously changed and modified without departing from the spirit and scope of my invention.

I claim as my invention:

1. In a portable piston actuated pneumatic tool having a casing, a handle closing the rear end of the casing and removably secured thereto, a one-piece crank shaft in said casing for actuating the pistons of the tool with the forward and rear ends of said shaft journaled in the casing and handle, respectively, two counter-weights on said shaft, one adjacent each end thereof, said shaft adjacent its

rear end having a shoulder and flat and curved surfaces adjacent the same, the rear counter-weight having its bore shaped to be held on the shaft by said flat surfaces, and means carried by said handle and engaging said weight for holding the same against said shoulder.

2. In a portable piston actuated pneumatic tool having a casing, the combination with a handle closing the inner end of the casing and removably secured thereto, of a one-piece crank shaft in the casing for actuating the pistons of the tool with the forward and rear ends of the shaft journaled in the casing and handle, respectively, two counter-weights on said shaft, one adjacent each end thereof, the rear counter-weight having removable connection with said shaft, the journal for the rear end of the shaft being an antifriction bearing having inner and outer bearing rings with bearing balls therebetween, the outer ring seating in a recess in the handle to prevent endwise movement of the shaft in one direction, and a steel disc clamped in position between the handle and casing and engaging the outer ring for holding the shaft against endwise movement in the opposite direction.

3. In a portable piston actuated pneumatic tool having a casing, the combination with a handle closing the inner end of the casing and removably secured thereto, of a one-piece crank shaft in the casing for actuating the pistons of the tool with the forward and rear ends of the shaft journaled in the casing and handle, respectively, two counter-weights on said shaft, one adjacent each end thereof, the rear counter-weight being removably mounted on said shaft, said shaft having a shoulder in front of said rear counter-weight, the journal for the inner end of the shaft having inner and outer rings with bearing balls therebetween, the outer ring seating in the recess in said handle, and a steel disc clamped between the handle and casing and having its inner portion extending over and engaging the outer ring on the outside thereof, said disc having its central portion flexed out of the plane of its outer edge when clamped between said handle and casing.

In testimony that I claim the foregoing as my invention, I affix my signature this 12th day of Dec., A. D. 1922.

IVER A. HANSSEN.
